BENJAMIN H. REED, OLMSTED A. REED, AND ALBERTO N. REED, OF HIGHTSTOWN, NEW JERSEY.

DRAIN-TILE.

1,220,891.

Specification of Letters Patent. Patented Mar. 27, 1917.

Application filed August 17, 1915. Serial No. 45,897.

To all whom it may concern:

Be it known that we, BENJAMIN H. REED, OLMSTED A. REED, and ALBERTO N. REED, citizens of the United States, residing at 5 Hightstown, in the county of Mercer and State of New Jersey, have invented certain new and useful Improvements in Drain-Tiles, of which the following is a specification.

10 This invention relates to drain tiles, and one object is to provide a tile of increased strength, stability and carrying capacity. Another object is to provide a main tile so constructed that branch tiles can discharge 15 water thereinto in a more efficient manner than has been heretofore possible with tiles now in use.

In order that the invention may be readily understood, reference is had to the accompanying drawing, in which

Figure 1 is a perspective view of a section of the improved drain tile;

Fig. 2 is a similar view showing a special section which may be employed at points 25 where branch drains connect with the main drain;

Fig. 3 is an end view of a main drain tile with two branch tiles communicating therewith, parts being in section;

30 Fig. 4 is a plan view of the tile system shown in Fig. 3; and,

Fig. 5 is a longitudinal vertical section through a system of tiles such as shown in Figs. 3 and 4.

35 Referring to the drawings in detail, the standard tile section is designated by the reference character A, and the special section, used for branch connections, by the reference character B.

40 The tile section A has a flat bottom 1, and side walls 2 extending upwardly therefrom at substantial right angles thereto. The top of the tile is semi-cylindrical in shape so as to form an arch 3. Below the arch is 45 a horizontal brace wall or partition 4, rigidly uniting the side walls and dividing the tile into an upper compartment, segmental in cross section, and a lower compartment substantially rectangular in cross section.

50 The side walls are preferably provided with a series of small openings 5 through which water may seep into the drain. It will be noted that the tile has its maximum width at the bottom so that its carrying capacity 55 is relatively as great when the water is

shallow, as when the tile is nearly full. In this respect the improved tile shown herein is different from the round or sole tiles heretofore employed, in which latter tiles the maximum carrying capacity is not 60 reached until the tile is approximately half full of water.

A special tile section, employed for branch tile connections is shown in Fig. 2, and is identical with the tile shown in Fig. 1 65 except that it is provided, adjacent one end with a notch 6, adapted to receive the end of a branch drain. It will be noted that this notch is formed just above the partition wall 4. It may be readily cut out of the tile 70 when the latter is in a soft condition.

In some cases, where desirable, a hole may be cut in a tile section, by means of a cold chisel, or otherwise, wherever it is necessary to connect with a branch drain, but such 75 holes should always be cut above the partition wall.

In Figs. 3, 4, and 5, are shown main and branch tiles connected in the manner above described and assembled in the relation 80 which they might well occupy in actual use. The branch tiles 7 are relatively small and preferably circular in cross section.

As clearly shown in Fig. 5, these branch tiles discharge their water into the upper or 85 segmental chamber of the main tile, at a point above the partition wall, and such water flows along on the partition wall, gradually discharging downwardly into the lower chamber through the more or less 90 open joints 8, between the ends of the tile sections. In this way, the discharge of water from the branch tiles is not interfered with by any water which may have accumulated in the lower compartments of 95 the main tile. Where branch tiles are connected, as heretofore, to a main tile on the same level, the flowage of water therethrough is often impaired by reason of water which may have accumulated in the 100 main tile. By use of the present invention, difficulties of this kind can be avoided, and free flow from the branch drains at all times insured.

Moreover, the upper or segmental compartment acts in the nature of an air chamber through which fresh air may flow and displace the sluggish air, saturated with moisture, which occupies the lower compartment, in contact with the water. Such fresh 105 110

air being not so saturated, and probably of a different temperature and density, tends to cause a circulation through the compartments and joints of the tile, and thus prevents stagnation.

One of the most important functions of the partition wall 4 is to brace the tile and greatly increase the mechanical strength thereof. The arch-shaped top of the tile is capable of withstanding great pressure and the brace wall 4 serves to tie the side walls together and prevent crumpling, buckling, or crushing by the weight of the overlying earth. The flat bottom of the tile, in addition to affording a maximum carrying capacity at low water levels, makes it easy to place and retain the tile sections in position while they are being laid.

What we claim is:

20 A drain tile system comprising a main drain having a flat bottom, an arched top,

side walls, and a horizontal partition wall extending between said side walls parallel with said bottom and dividing the tile into an upper compartment, segmental in cross section, and a lower compartment substantially rectangular in cross section, in combination with branch drains tapping the upper compartment of said main drain above the partition wall thereof, said main drain being composed of sections having comparatively open joints between them, whereby water discharged into the said upper compartment from said side drains can escape downwardly through such joints into the lower compartment.

In testimony whereof we have affixed our signatures.

BENJAMIN H. REED.
OLMSTED A. REED.
ALBERTO N. REED.
